Specification of Letters Patent. Patented Apr. 30, 1918.

Application filed March 16, 1914. Serial No. 825,049.

To all whom it may concern:

Be it known that I, CHARLES L. MOHR, a citizen of the United States, and a resident of Janesville, county of Rock, and State of Wisconsin, have invented certain new and useful Improvements in Linotype-Machines, of which the following is a specification.

My invention relates to improvements in so-called linotype or slug casting machines and has special reference to improvements in devices for the production of linotype or printing slugs of predetermined lengths.

The object of my invention is to provide a linotype machine which shall be readily and easily adjustable to produce printing slugs of certain desired lengths without the necessity of changing the length of the mold slot in which the slugs are cast.

A further object of my invention is to provide a line casting machine in which the means which control the length of the line of matrices assembled, and the means which hold the line of matrices in casting position, shall be connected for adjustment to coöperative positions for the formation of slugs with printing surfaces varying in length throughout the capacity of the machine.

A further object of my invention is to combine the several related adjustments upon a linotype machine relatively to the production of a slug which has a printing surface shorter than the normal length of the slug, so that they shall all be simultaneously made or produced by the operation of but one adjusting or controlling device.

A further object of my invention is to reduce the labor and time required to make the several adjustments which are necessary for the production of slugs having printing surfaces of different lengths; and to eliminate the possibility of accident incident to such changes and which may result, from the inadvertence or carelessness of the operator in starting the machine before having made all the adjustments which are necessary when a change in the length of the printing portion of a slug is desired or attempted.

My invention resides in a linotype or line casting machine provided with means for casting or forming a slug of definite or normal length, mechanism for controlling the formation of a line of matrices and for adjusting the vise jaws which hold the line of matrices in casting relation to the mold, to corresponding positions, to produce slugs

having printing surfaces equal to or less than the length of the mold, and means for cutting the slug to the desired length, said mechanism being also arranged for adjusting the cutting means to a position corresponding with the adjustments of said other parts.

My invention further resides in a slug-casting machine of the linotype class provided with a cutter for cutting the slugs to a predetermined length as they are ejected, means for adjusting the cutter to vary the length of the finished slug, and means connected with said adjusting means for correspondingly adjusting a stop controlling the length of the line of matrices and for positioning one of the vise jaws for holding the line of matrices in position and in relation to the slug casting mold.

My invention further resides in a line-casting machine provided with a slug mold movable from a casting position to an ejecting position, means, associated with the mold, when it is in casting position, for holding a line of matrices of predetermined length for coöperation with the mold for casting the printing slug, means for limiting the length of the line of matrices as the matrices are assembled and mechanism adjusting said limiting and holding means to corresponding positions, an ejector associated with the slug mold and related to its ejecting position for ejecting the slug from the mold, a cutter for cutting the slug in two pieces as it is ejected, said adjusting mechanism being also connected with the cutter and adapted to set the cutter to correspond with the adjusted positions of the assembler stop and the vise jaw.

My invention further consists in a linotype machine having a slug casting mold and means for holding a line of matrices in relation to the mold, means for adjusting said holding means for lines of matrices which are of different lengths, an assembler stop on said machine and connection between said holding means and said assembler stop, whereby when said holding means are adjusted to hold a line of matrices of certain length said stop will also be adjusted to limit the formation of a line of matrices to equal length therewith.

My invention also consists in the several features of construction, and the combinations and arrangements of parts, whereby

the above mentioned and other objects are attained, and made possible, and all as hereinafter described and claimed.

My invention will be more readily understood by reference to the accompanying drawings, forming a part of this specification, and in which:

Figure 1 is a perspective view of a portion of a linotype machine as seen from the front;

Fig. 2 is a horizontal sectional view substantially on the line 2—2 of Fig. 1:

Fig. 3 is a transverse vertical sectional view on the line 3—3 of Fig. 2;

Fig. 4 is a vertical sectional view substantially on the line 4—4 of Fig. 2;

Fig. 5 is a vertical sectional view on the line 5—5 of Fig. 2;

Fig. 6 is a front elevation of the assembler mechanism showing a line of matrices assembled;

Fig. 7 is a detail vertical section on the line 7—7 of Fig. 2;

Fig. 8 is a detail vertical section substantially on the line 8—8 of Fig. 2;

Fig. 9 is an enlarged horizontal section substantially on the line 9—9 of Fig. 1;

Fig. 10 is a vertical section substantially on the line 10—10 of Fig. 9;

Fig. 11 is a detail horizontal section on the line 11—11 of Fig. 10, the upper part of the saw casing being removed;

Fig. 12 is a vertical sectional view substantially on the line 12—12 of Fig. 11;

Fig. 13 is a side elevation of the slug ejector and its operating mechanism;

Fig. 14 is an enlarged rear elevation partly in section showing the yielding stop on the ejector operating lever;

Fig. 15 is an enlarged front elevation showing the slot through which the slug is ejected;

Fig. 16 is a horizontal section on the line 16—16 of Fig. 15;

Fig. 17 is an enlarged section on the line 17—17 of Fig. 8;

Fig. 18 is a perspective view of the saw arbor shown in an inclined position to facilitate repairs;

Fig. 19 is a detail vertical section of the bearing of the saw arbor;

Fig. 20 is a detail vertical section showing the clutch on the saw arbor; and

Fig. 21 is a detail horizontal section of the slug discharge chute on the line 21—21 of Fig. 10.

In the adjustment of linotype machines for the production of printing slugs which are shorter than the normal length, or which have printing surfaces shorter than the slug, several different methods are employed. One method is to change the liners which hold the mold sides apart to produce slugs of the desired length. This, however, requires the changing or adjustment of the

ejector and several other adjustments in the machine and when it is desired to produce but a few slugs of a shorter length, the time consumed in making the several adjustments is so great that this method is not generally satisfactory. Another method is to make use of the full or the normal length of the mold slot and when this method is used it is necessary when it is desired to produce a printing slug of a shorter length than the length of the mold, to adjust the assembler slide to receive a certain measure or number of matrices to fill the length of the line which it is desired to print and to adjust at least one of the vise jaws to clamp the short line of matrices. It is usual to hold the line of matrices with one end even with one end of the mold slot with a fixed jaw, and to hold the line of matrices against this fixed jaw by means of a movable vise jaw which is adapted to cover the part of the slot which is not covered by the line of matrices and which casts the slug partly blank. The result of this method is to produce a slug which has printing characters covering a certain length upon one end and the balance of which is blank. The usual method employed is to take this slug to a saw table and saw off the blank end, reserving the end carrying the type characters for use. There have been devices made by means of which such a slug may be cut apart, or cut into two pieces as it is being removed from the linotype machine, but with the use of such devices, so far, it has been necessary to make the several adjustments above spoken of independent of each other and it sometimes occurs, in the hurry and rush of this class of work, that one or the other of the necessary adjustments is not made. If the adjustment which is overlooked is that of moving or placing the vise jaw into its proper position the result may be quite disastrous, as under some conditions there is nothing to prevent the escape of the molten metal through the mold, and into the various parts of the machine which are located in front of the mold. By means of my invention I am enabled to combine these several adjustments in such a manner that the operator may have assurance that when he has made one of them all of them will have been made and that the possibility of accident resulting to himself or to the machine from the non-adjustment of one of these parts is eliminated. In other words, I have connected the assembler stop with the vise jaw in such a manner that when the vise jaw is placed to receive a certain length of line of matrices the assembler stop is likewise adjusted to control the formation of that certain quantity of matrices, and when I desire to sever or cut the slug at the point corresponding with the length of the line of matrices, the single operation of adjusting

the position of the vise jaw also adjusts the position of the cutter, which is arranged in front of the slot through which the slug is ejected from the machine, to a position 5 which will accurately cut the slug to the length desired.

It is frequently necessary when setting up display matter, or matter in which cuts are used, to produce slugs of the proper 10 length to fill out the lines at the side of the cut. The cut is sometimes irregular in outline and in filling in at the side of the cut it may require a few slugs of one length and then a few slugs of another length. By 15 means of my invention I can adjust the several parts, that is, the assembler stop, the vise jaw, and the cutter, to produce slugs of a certain definite length and I have arranged a stop and a holder in such relation 20 to one movable member of my device so that after having set the several parts to produce slugs of a certain length, I can then adjust the several parts in relation to said stop, measuring the adjustment by the cut itself, 25 whereby the length of the slug to be produced is reduced by the width of the cut and consequently the slug which is produced added to the width of the cut will fill the space or be of the length which is desired. 30 In illustrating my invention I have shown sufficient of the well-known so-called linotype machine as is necessary to illustrate the application of my invention thereto. As hereinbefore explained, my invention is associated with the mold wheel, the assembler mechanism, the mechanism for clamping the matrices when the cast is made, and the ejector mechanism for forcing the slug out of the mold wheel.

40 In said drawings, A represents the usual mold wheel of a linotype machine; B represents generally the assembler mechanism; C represents generally the mechanism for clamping the line of matrices at the time the cast is made; D represents the ejector mechanism; and E represents generally the movable frame of a linotype machine which is arranged in front of the mold wheel and which commonly carries the clamping mechanism and the stick or support upon which the slugs are assembled as they are ejected from the machine. As commonly constructed, the mold wheel A is mounted on a horizontal axis and is provided with a number 45 of molds, a¹ near its periphery, and this mold wheel is adapted to be rotated from time to time to set the molds successively in the casting and ejecting positions. This wheel is commonly operated by means of a 50 pinion, a² which meshes therewith. Arranged at one side of the mold wheel is the assembler mechanism B, wherein and whereby the matrices are assembled in line and thereafter, at the proper time, transferred 55 by mechanism, not shown, to a position in

front of the mold wheel where the line is adapted to be tightly clamped against the mold wheel at the time the slug is cast. The movable frame E comprises vertical standards e¹, which rise from the lower part of 70 the machine, and a rigid cross bar e² which is arranged in front of the upper part of the mold wheel. The framework E is commonly arranged to be tipped out from the machine on pivots arranged at the lower part 75 of the machine, so that the various working parts associated with the mold wheel can be inspected, and to be held in working operation or position by means of hand clamping bolts e³. The horizontal bar e² at the upper 80 end of the frame E carries two oppositely disposed jaws e¹ and e². The jaw e¹ is substantially stationary, and serves to form an abutment for one end of the line of matrices e⁴. The jaw e² is movable back and forth in 85 relation to the fixed jaw on the bar e² in order to adjust the two jaws to clamp lines of matrices of different lengths. In Fig. 2 I have shown the mold a¹ in the wheel A, and the jaws positioned in relation thereto, 90 the jaw e¹ being substantially at one end of the mold and the jaw e² shown spaced from the jaw e¹ to receive the short line of matrices e⁴. The line of matrices is shown 95 as being about half the length of the mold, and the jaw e² is of sufficient length to cover the remaining portion of the mold, so that when the slug is cast the portion of the slug covered by the jaw e² will be blank and the portion of the slug covered by the line of 100 matrices will be provided with printing characters.

My invention is particularly related to the means for setting the jaw e² in relation to the jaw e¹, so that the line of matrices 105 whether shorter or longer will be properly clamped in position, and associated therewith is the adjustment or regulation of the stop which controls the length of the line of matrices which is being formed, so that 110 the line of matrices as formed, when transferred to the position between the vise jaws will be properly clamped.

As clearly illustrated in Fig. 3, the vise jaw e² is mounted in and fits a longitudinal 115 L-shaped groove e⁴ provided in the cross bar e². This jaw is relatively long and is adapted to slide back and forth into different positions relatively to the mold and to be guided in its longitudinal movement and held in alinement by the vertical projection e⁵ thereon which fits within the L-shaped groove e⁴. For the purpose of moving the jaw e² longitudinally in the groove 120 e⁴ I provide a screw shaft e⁶ which lies within the groove e⁴ and carries a nut e⁷ thereon which also fits within the groove and is thus prevented from rotating with the shaft e⁶. The nut e⁷ is adapted to be forced against 125 the rear end e⁸ of the vise jaw e² and thus 130

force or draw the jaw c^2 toward the jaw c^1 . The movement of the jaw toward the nut, when the nut is moved in the opposite direction, is accomplished by the usual linotype mechanism for this purpose, that is, the jaw c^2 is free to move toward the jaw c^1 , but cannot move to lengthen the distance between the jaws beyond the position controlled by the nut c^7 . For the purpose of 10 rotating the shaft c^8 I provide a vertical shaft c^9 mounted in the cross bar e^2 and provided with a screw gear c^{10} adapted to mesh with a similar screw gear c^{11} carried by the shaft c^8 . The shaft c^9 I arrange to be rotated by means of a hand wheel c^{12} mounted 15 on a shaft c^{13} which carries, at its inner end, a bevel gear c^{14} adapted to mesh with a complementary bevel gear c^{15} mounted on the upper end of the shaft c^9 to rotate therewith. 20 By means of this construction I am enabled to arrange the hand wheel or disk c^{12} , which is provided with an operating handle c^{16} , in a convenient position to be rotated by the machine operator when he desires to adjust 25 the several parts of my mechanism.

For the purpose of associating the stop which controls the length of the line of matrices being assembled with the vise jaws which clamp the line when formed, I secure 30 a rod c^{18} to the nut c^7 . This rod lies in the L-shaped slot e^4 , in which the jaws are mounted, and projects from the end of the bar e^2 toward the assembler mechanism B, and is provided on its end with a horizontally projecting tapered pin c^{19} which, as 35 will be described, serves to connect the jaw c^2 with the assembler stop, and this pin, as shown in Fig. 7, enters a slot provided in a bar forming part of the assembler mechanism. The assembler mechanism, in so far as 40 my invention relates thereto, comprises an assembler bar b^2 mounted to slide back and forth upon the frame b^8 of the linotype machine. This bar is provided with a vertical stop b^4 arranged in front of the assembler channel b^5 and is adapted, as the matrices are assembled, to move away from the assembler channel sufficient to admit the matrices as they are assembled. The stop b^4 is 45 rigid with the bar b^2 and moves therewith. The bar is shown as being mounted for movement between suitable anti-friction rolls b^6 . The rear end of the assembler bar carries a stop b^7 which can be adjusted longitudinally 50 of the bar if desired, but which is usually arranged or placed adjacent to the rear end of the bar and moves therewith. This stop projects from the front of the bar and is adapted to control the movement of the bar 55 by being brought into contact with an adjustable stop b^8 which I mount upon a horizontal movable bar or rod b^9 arranged in front of the assembler mechanism and mounted for longitudinal movement in the outer ends of brackets b^{10} and b^{11} . The stop 60

b^8 is rigid with the bar b^9 and when the bar b^9 is adjusted to the desired position and held against longitudinal movement, the stop b^7 serves to limit the movement of the assembler bar and prevent the formation of a 70 line of matrices longer than that which is desired. The end b^{12} of the bar b^9 which projects toward the mold wheel is provided with the slot b^{13} adapting it to receive the projection c^{19} on the connecting rod or bar 75 c^{18} . The projection c^{19} transversely fits the slot b^{13} and thus holds the bar b^9 against longitudinal movement. The slot b^{13} is vertically elongated and the projection c^{19} is tapered so that as the frame E which carries the vise jaw is moved up to its operating position the pin or projection c^{19} will readily enter the slot b^{13} without difficulty, and it is thus arranged so that it will easily withdraw 80 from the slot so that the two parts may be automatically disconnected without attention by the operator when the frame E is withdrawn from its operating position. I have illustrated in Fig. 1 the line shifter finger b^{14} which is adapted for movement with 85 the assembled line of matrices as the same is transferred from its assembled to its casting position and to contact with the vise jaw c^2 , and move it back against the nut c^7 should it happen that the vise jaw is not in 90 contact with the nut c^7 at such time.

In order that the operator may know the exact position of the vise jaw c^2 , I provide a scale c^{21} on the projecting end c^{20} of the rod c^{18} . This scale has divisions, one pica or one-sixth of an inch in length and I provide a fixed indicator c^{22} projecting from the end of the bar e^2 coöperating with the scale to show the position of the vise jaw e^2 or, in other words, to indicate the length of the 100 line of matrices. And further, the scale also shows the position of the assembled stop b^8 .

For the purpose of indicating the accurate or fine adjustment of the vise jaw and assembler stop, I preferably arrange the gearing which connects the hand wheel c^{12} with the nut c^7 so that one revolution of the hand wheel advances the nut one pica or one division of the scale c^{21} and I provide a 110 scale c' on the hand wheel c^{12} which I divide into twelve parts; each division thereof represents one "point" in the movement of the vise jaw. I fix an indicator c''' to a rigid 115 part of the machine and so arrange the several parts that when a certain division of the scale c' is beneath the indicator c''' the indicator c^{22} is even with one of the divisions on the scale c^{21} .

Thus far described the mechanism relates 125 particularly to the coördinate or simultaneous adjustment of the vise jaw and the assembler stop, and, as has hereinbefore been explained, a further object of my invention is the cutting of the slug, as it is ejected 130

from the machine, to remove from the slug the portion which is cast blank and to preserve the portion of the slug which is provided with printing characters. I make use 5 of the frame E upon which to secure the slug cutting mechanism which I designate generally by F. This mechanism, as shown, comprises a circular saw f¹ mounted upon the lower end of a saw shaft or arbor f² 10 which is rotatably mounted in a bearing f³ carried by the bracket f⁴ which forms the bearing for the shaft e¹, and the bracket f⁴ is rigidly mounted upon the cross bar e². The saw f¹ is mounted within a closed casing f⁵ which is vertically movable and is secured in position by means of a bracket f⁶ which projects horizontally from the lower part of the casing. This casing is divided 15 horizontally into an upper and a lower part f⁷ and f⁸, respectively, which are clamped together by the thumb screws f⁹. This bracket is adapted to be secured in position upon a vertical guide or slide f¹⁰ secured to the frame E by means of a screw f¹¹ adjacent its upper end, and a second screw f¹² at its lower end. Associated with the bracket f⁶ is a vertically movable nut f¹³ which receives a screw threaded shaft f¹⁴ mounted in bearings formed in the ends of said slide 20 f¹⁰. This screw threaded shaft f¹⁴ practically forms an extension of the vertical shaft e² which carries the screw gear e¹⁵, that is, it is adapted to be rotatably connected to the shaft e² to rotate therewith by 25 mechanism hereinafter to be described. Suffice it to say that when the vertical shaft e² is rotated and the shaft f¹⁴ is connected thereto the saw casing f⁵ will be moved vertically when the operator turns the hand 30 wheel e¹⁶ to adjust the position of the vise jaw and the assembler stop. The shaft f² upon which the saw is mounted is vertically movable, its upper end being provided with a key slot f¹⁷ adapting it to move through 35 the bearing in which the upper end is carried. This saw shaft is adapted to be rotated at high speed by power derived from an electric motor G mounted upon the frame E and operatively connected to the shaft by 40 means of a drive belt g¹. The bracket f⁴, in which the upper end of the shaft f² is mounted, is provided with an internal spherical bearing surface f¹⁸ and I provide a spherical ball bearing f¹⁹ which is rigidly 45 mounted upon a sleeve f²⁰. The sleeve is of a length to project both above and below the bracket f⁴, and upon its lower end I secure a grooved belt pulley f²¹ and upon its upper end a small fly-wheel f²². The sleeve 50 is also provided with a fixed key f²³ which slides in the key slot f¹⁷ and permits the shaft to move vertically through the bearing.

The function of the fly wheel is to aid 55 the motor at the time the slug is being cut, for the motor is preferably of such small power that without the fly wheel the motor would not drive the saw, but as the cut is made almost instantaneously the fly wheel prevents the slowing of the saw due to the cutting of the slug. To cause the saw casing with the saw to be adjusted up and down in unison with the adjustment of the vise jaw and the assembler stop, I connect the nut f¹⁰ with the bracket f⁶ by means of a clamping bolt f²⁴ which screws tightly into the side of the nut f¹⁰ and projects through a free hole f²⁵ in the bracket f⁶. The outer end of this rod is threaded and receives a clamping nut f²⁶ by means of which the bracket f⁶ 75 and the nut f¹⁰ can be tightly clamped to the guide f¹⁰ or can be freed from the guide sufficient to permit the free movement of these two members upon the guide. The guide is provided with inwardly projecting 80 ribs f²⁷ upon which the two members f⁶ and f¹⁰ are adapted to be clamped.

Fig. 18 particularly illustrates the possibility of tipping the saw arbor or shaft into an inclined position, when it is desired to 90 examine or repair the saw. This is made possible by the spherical bearing f¹⁴ in which the upper end of the shaft is mounted, and it will be readily understood that when the screws f⁹ are removed the saw 95 with its arbor and the upper part f⁵ of the casing can be raised and the shaft can be swung out, as shown. I arrange the saw in such relation to the mold wheel that it stands in position in front of the mold slot 100 through which the slug is to be ejected, and in such position in relation thereto that as the slug is ejected the saw will cut the slug in two. In connection with the saw I arrange a chute f²⁸ above the saw through 105 which the blank portion of the slug is automatically removed and a slide or slot below the saw through which the printing portion of the slug may be assembled with others in column form upon the stick K, 110 forming a part of and carried by the frame E.

The mold wheel, as shown, is provided with four molds, and is adapted to position a mold at the top of the wheel at the time 115 a slug is formed in the mold and to position the mold 90° in advance from the casting position to bring it to the ejecting position. The mold in which the cast is made is at the upper part of the wheel, and the mold 120 from which the cast slug is to be ejected is at the side of the wheel, that is 90 degrees in advance of the mold in which the slug is cast. A linotype machine of the form illustrated is provided with the slug-ejecting 125 mechanism D adapted to eject the slug from the mold when brought to the ejecting position, as described. The slug ejecting mechanism comprises a fixed slide d¹ in which the ejector proper d² is adapted to be moved 130

6

back and forth. This ejector is provided with a thin plate d^3 on its forward end adapted, as the ejector proper is moved forward, to project through the mold in the 5 wheel and force the slug forward therefrom. To move the ejector back and forth a swinging lever d^4 is provided pivoted in the lower part of the machine and having its upper part connected to the ejector by means 10 of a link connecting rod d^5 . This lever is provided with an arm d^6 which projects into close contact with a cam wheel d^7 which is mounted within the machine for rotation. This cam wheel carries a fixed stop d^8 which 15 is adapted to contact with a projection carried on the end of the arm d^6 , the wheel moving in the direction shown by the arrow on Fig. 13, and move the lever forward, thus moving the ejector forward through the 20 agency of the link d^5 . At a certain point in the movement of the lever and of the rotation of the cam wheel, the stop d^8 is released or slips off from the lever and the lever thus stops its forward movement. The lever is 25 adapted to be returned to its former position by means of a cam surface d^9 provided on the face of the wheel d^7 and which is adapted to contact with a projection d^{10} provided on the lower part of the lever. As indicated in 30 Fig. 2 the ejector is arranged very close to the melting pot a^8 and as this pot and the surrounding metallic parts of the machine become more or less highly heated, and as the ejector and its various parts are relatively long their change of length, due to 35 change of temperature, may be considerable. Further, it is necessary for perfect work to arrange the ejector plate so that its outer end approaches very closely to the edge of 40 the saw f^1 , which is cutting the slug and yet it must never touch the saw. If the plate touches the saw it will tend to destroy it, that is, the saw will have the teeth dulled. To prevent the plate touching the saw at the 45 time of its extreme forward movement and yet permit the plate to approach practically into contact with the saw I provide means whereby the plate can be forced forward to the limit of its forward movement, and I 50 provide a stop by which its forward end is definitely positioned relatively to the saw, and I provide a yielding device between the stop d^8 and the ejector so that when the ejector is brought to a dead stop the mechanism which is pushing it may yield sufficiently 55 to prevent damage thereto. As shown in Fig. 13, I provide an adjustable stop d^{11} mounted on a part of the ejector which is rigid with the blade d^3 and adapted 60 to contact with a rigid cross bar d^{12} secured to and upon the slide d^1 . The plate d^3 of the ejector projects beyond the end of the stop d^{11} a relatively small proportion of the total distance from the outer end of the blade 65 to the connection with the lever d^4 and con-

sequently when the stop d^{11} is adjusted to permit the end of the plate to come into close relation with the edge of the saw f^1 , but not touch the same, this adjustment is definite and permanent regardless of changes of temperature and consequent changes of length. I secure the stop d^{11} in its position by means of a jam nut d^{13} . To make allowance for the variation in length of the ejector and the link d^5 , I provide upon the outer end of the arm d^6 a stop d^{14} which lies in the path of the stop d^8 carried by the cam wheel d^7 , and as the stop d^{14} is carried by the swinging lever d^4 the stop d^{14} moves out of the path of the cam stop d^8 as the lever swings forward and it is so arranged that it will pass out of contact therewith at the time that the ejector slide reaches the forward limit of its movement. The stop d^8 instead of contacting directly with the stop d^{14} contacts with a pivoted plate d^{15} mounted upon the stop d^{14} and movable from and toward the same. This plate is mounted on the stop d^{14} by the pivot d^{16} arranged adjacent to one end of the plate. The opposite end of the plate is held spaced from the stop d^{14} by means of a relatively stiff coiled spring d^{17} . This spring is arranged within a pocket or hole d^{18} provided in the stop d^{14} . The cam stop d^8 contacts with the plate d^{15} immediately over the spring d^{17} and I make the spring d^{17} of such a strength that as long as the stop d^{11} does not contact with the bar d^{12} the spring is strong enough to move the ejector and eject the slug, but when the stop d^{11} contacts with the bar d^{12} , and thus is prevented from further forward movement, the spring d^{17} yields sufficiently to permit the final forward movement of the stop d^8 and thus allow it to be carried out of contact with the lever d^4 and be freed therefrom.

As clearly shown in Fig. 9 the ejector blade d^3 is preferably thinner than the slug slot a^4 and is long enough to eject the slug H , through the mold and through the slot e^5 provided in the frame E , the saw f^1 being arranged in front of and in close relation to the slot e^5 . Between the mold and the slot e^5 knives e^8 are arranged to trim the side faces of the slugs as the same are ejected from the mold slot. The saw f^1 , as heretofore described, is inclosed in the casing f^2 and is held upon the lower end of the shaft f^2 by means of a fixed collar f^{10} and a clamping nut f^{11} . This collar and nut form shoulders which closely fit between fixed shoulders f^{12} of the casing f^2 and consequently when the casing f^2 is raised and lowered by the mechanism heretofore described the saw is adjusted vertically in relation to the slot through which the slug is ejected. Set collars f^6 prevent the end-wise movement of the screw shaft f^{11} in its bearing. The chute f^{13} through which the blank portions of the slugs escape is carried

by the saw casing f^6 to be raised and lowered therewith and is arranged in such a manner that the blank end of the slug H drops from the upper surface of the saw and slides 5 down the chute, the saw rotating in the direction of the arrow, as shown in Fig. 9, carries the blank portion of the slug through the first part of the chute f^{23} which is arranged above the saw to the downwardly inclined 10 portion f^{28} down which the blank portion of the slug falls by gravity. In cutting the slug the metal of the slug tends to adhere to the surfaces of the saw and prevent that exact cutting of the slugs which is necessary. 15 To prevent this action I constantly oil the upper and lower surfaces of the saw adjacent to its periphery and for this purpose I provide pockets f^{29} and f^{30} within the casing f^6 , one above and the other below the 20 saw, and arranged adjacent to the periphery thereof. I fill these pockets with felt or some similar absorbent substance f^{31} contacting with the surfaces of the saw, and I provide the casing with an oil cup f^{32} communicating with the upper pocket through an oil duct f^{33} and with the lower pocket by means of an oil duct f^{34} . This oil cup serves to keep the absorbent pads f^{31} soaked with oil and they in turn lubricate the saw. For 25 the purpose of conveniently determining the adjustment of the saw in relation to the adjustment of the vise jaw and the assembler stop, I arrange a scale f^{35} in vertical position adjacent to the saw casing f^6 . I secure 30 the scale at its lower end to a portion of the stick or platform K and arranged parallel with the shaft f^2 . I also provide a stop f^{36} secured to the casing f^6 and projecting close to the gage or scale f^{35} and 35 adapted to slide up and down in relation to the scale as the saw is raised and lowered. This scale is figured the same as the scale e^{21} , which indicates the adjustment of the vise jaw. I also provide a movable stop f^{37} 40 for use upon the scale f^{35} when it is desired to adjust the mechanism for reducing the length of the slug to correspond with or complementary to a cut with which the completed slug is to be used. In other words, if the 45 mechanism has been adjusted to produce a printing slug, we will say, of seventeen ems length and it may be desired to associate the slugs being formed with a cut of six ems length, I place the adjustable stop f^{37} 50 in contact with the upper surface of the stop f^{36} on the scale f^{35} and then I operate the mechanism to lower the saw. As indicated in dotted lines in Fig. 10, I place the cut f^{38} between the upper surface of the 55 stop f^{36} and the lower surface of the stop f^{37} , and then raise the saw until the cut just fills the space between these two stops. In this manner the saw is lowered from the 60 position in which it would produce a seventeen em long slug exactly the length of the 65 cut; that is, it is lowered exactly, in the instance mentioned, six ems and the slug produced is consequently eleven ems long instead of seventeen ems long, and which, with the cut of six ems, produces a complete 7 line seventeen ems long. In consonance with this adjustment of the position of the saw the assembler stop and the movable vise jaw are likewise adjusted. The discharge slot f^{24} through which the completed slugs fall, as best shown in Fig. 10, carries the slugs down upon the upper surface of the slug-assembling stick K . I provide a curved plate k^1 at the lower end of the slot f^{24} adapted to guide the lower end of the slugs outwardly upon the plate K . The lower part f^{39} of the saw casing f^6 is cut away in front of the slot through which the slug is ejected to permit the upper end of the lower part of the slug to emerge and the casing 85 itself forms a stop in front of the upper end of the finished slug which prevents the slug from falling forward when the lower end strikes the curved plate k^1 and causes the slug to slide down upon the plate K 90 with its printing face uppermost. I also provide an adjustable stop k^2 in the path of the upper ends of the lower parts of the slugs to guide them as they descend. This adjustable stop k^2 is particularly useful at times when the saw is raised completely cut of the path of the emerging slug, that is, when it is desired to produce slugs of full-mold length and not cut them with the saw. This stop is mounted upon the upper end of a rod or wire k^3 which I secure to the edge of the stick K by means of a screw k^4 and a washer k^5 . By loosening the screw this stop may be readily adjusted vertically. In addition to the stop k^2 I provide a side wing k^6 which prevents the slugs from falling sidewise, the opposite side of the slug being held by a fixed plate or guide k^7 . As illustrated in Fig. 10, the lower portion of the slug, which carries the type characters, immediately it has been severed from the upper portion, drops down endwise upon the curved plate k^1 , and its lower end slides down the stick K , the upper end being held against forward movement by the saw frame or the stop k^2 and consequently the slug is caused to rest upon the stick with its printing characters uppermost. As clearly shown in Fig. 1, the slug falls down the stick in front of a movable member k^8 which moves back and forth to permit the descending slugs to take their positions upon the stick, and to force the assembled slugs forward along the stick in the usual manner. 105 It is necessary to steady the slug as it is projected through the slot e^3 and on to the edge of the saw, and prevent it from any vibratory movement. To accomplish this I provide a swinging plate f^{39} forming one 110

side of the slot e^5 through which the slug is ejected. The rear edge of the plate is pivotally connected to one of the knives e^6 in such a manner that when the knife is moved from 5 and toward its companion knife, to change the thickness of the slug, the rear edge of this plate will be carried with the knife. This plate is spring-pressed and is normally held in the path of the slug, the slug forcing it outwardly against the spring pressure as the slug is forced through the slot e^5 . The plate is pressed inwardly by means of a U-shaped spring e^7 which is carried adjacent to or behind the plate. I provide a small pocket e^8 in the frame E to receive the mechanism which holds the plate, and which holds the movable knife e^6 . The spring e^7 is secured within this pocket by means of a screw e^9 and the movable knife is secured 20 by screws or bolts e^{10} having threaded ends which enter threaded holes in the movable knife and are adapted to clamp the knife to the rear face of the frame E. The screws are provided with spring washers e^{11} , so 25 that when the knife is tightened into position it can be adjusted without loosening the screws. Upon the outer ends of these screws I mount stops e^{12} having inner faces e^{13} which are adapted to contact with the 30 rear face of the outer edge of the plate e^9 , and adjustable beneath the heads of the screws e^{10} , to tightly hold the slug, as it is pushed through the slot e^5 , against the opposite face or wall of the slot. The friction 35 with which the slug is thus held as it is forced through the slot e^5 holds it against any vibration or movement therein as it is being sawed.

At times it is desirable, as heretofore explained, to make use of my device for adjusting the vise jaw and the assembler stop without cutting the slugs by means of the saw. At such times the mechanism is operated to raise the saw to the upper limit of 40 its movement where it is out of the path of the slugs as they are ejected, and then the threaded shaft f^{11} by means of which the saw casing is directly raised and lowered is disconnected from the shaft c^8 which connects the operating handle or disk e^{12} with the mechanism for adjusting the vise jaw, and assembler stop. The disconnection of 45 these two shafts is effected by means of a sliding clutch or collar f^{10} mounted upon the upper end of the shaft f^{11} to slide thereon, but to rotate therewith. This clutch is provided with a transverse slot f^{14} in its upper end and the lower end of the shaft c^8 is provided with a transversely arranged pin 50 f^{12} adapted to fit within the slot and when therein to rotate the collar f^{10} with the rotation of the shaft c^8 . This clutch is moved up and down by means of a vertical rod f^{13} mounted parallel with the shaft f^{11} and provided on its upper end with a fixed head

f^{14} provided with a notch f^{15} , in one side, adapted to engage the edge of a flange f^{16} on the collar f^{10} . This rod f^{13} is adapted to be moved up and down by means of a lever f^{17} pivotally mounted upon the lower end 70 of the frame f^7 which carries the screw threaded shaft f^{11} . When the outer end of the lever f^{17} is moved downwardly the clutch is raised and the shaft f^{11} is connected for rotation with the shaft c^8 and when the 75 outer end of the lever f^{17} is raised these two shafts are disconnected and thereafter the vise jaw and the assembler stop can be adjusted without moving the saw and at such times the saw, as has been explained, is out 80 of the path of the slug and consequently the linotype machine may be adjusted to produce slugs the full length of the mold and either having printing characters extending from end to end or formed blank on one end 85 if such are desired.

What might be termed the rough adjustment of the vise jaw has been explained heretofore, but for the exact and fine adjustment of the vise jaw in such a manner as to 90 tightly hold the line of matrices and yet be movable to permit the removal of the matrices after the cast is made requires a little further explanation. As has been explained, the vise jaw is adjustable by means of the 95 mechanism described through the medium of the screw threaded shaft c^8 and the nut c^7 which is carried thereby. The mechanism for the adjustment of the jaw c^8 for what is termed the "lockup" of the matrices will 100 be described by reference particularly to Figs. 4 and 5. The end of the shaft c^8 which carries the screw gear c^{11} , is mounted in a U-shaped bracket c^{22} which is secured 105 within the L-shaped slot or groove e^4 provided in the cross bar e^2 , and the gear c^{11} is so mounted that the shaft c^8 may slide longitudinally through the gear, but the shaft is provided with a key slot c^{23} to receive a key carried by the gear, consequently the 110 shaft rotates with the gear, and the gear is retained against other than rotative movement by the bracket c^{22} . The shaft is held against any but intentional endwise movement by the structure now to be described. 115 The opposite end of the shaft is provided with a button-head c^{24} adapted to fit within a slot c^{25} provided upon a movable member or block c^{26} . This block is also mounted within the slot or guide-way e^4 in the bar e^2 120 and is movable longitudinally therein. The shaft is movable with the block, but is mounted so that it may be rotated. Once the block c^{26} is adjusted and held tightly in position, it will be understood that the rotation of the 125 shaft c^8 will move the nut c^7 and adjust the position of the vise jaw c^8 , and if it were not required to relieve the pressure upon the line of matrices in order to remove them from their locked position this is all that would be 130

necessary. But in the form of machine illustrated it is necessary to permit the vise jaw to move backward or away from the line of matrices after the cast is made to relieve the line of matrices from pressure, so that they can be removed. For this purpose I provide for a slight backward and forward movement of the block c^{26} which carries the nut c^7 with it. To cause this backward and forward movement of the block c^{26} and consequently of the nut c^7 I provide an adjusting screw c^{27} which is mounted in a threaded opening c^{28} provided in the lower part of the block c^{26} . This screw has a large flange c^{29} on its outer end and is provided with a square end c^{30} to receive a wrench. As shown in Fig. 5, I mount a crank arm c^{31} upon the outer end of the screw c^{27} , and I secure it to the flange by means of a screw c^{32} . This arm is connected to a vertically disposed link c^{33} which depends therefrom, and this link is provided in its lower end with a slot c^{34} adapted to receive a pin carried by the end of a lever c^{35} . This lever c^{35} forms part of the linotype machine, and the end carrying the pin c^{36} is movable up and down to cause the arm c^{31} to rotate the screw c^{27} back and forth. A spring c^{37} is provided on the link c^{33} which normally holds the arm c^{31} at the upper limit of its movement and the jaw e^2 at the inner limit of its movement as controlled by the screw c^{27} .

The word "linotype", as used herein, denotes generally those machines as a class which are adapted to produce printing slugs, and is not limited to those particular machines known in the printing trade as linotype machines.

I do not herein claim my novel, saw lubricating device, such forming the subject matter of my co-pending divisional application, filed February 4th, 1918, Serial No. 215,289 entitled Improvement in the art of sawing metals.

45 I do not herein claim my novel, means for examining and removing the slug cutting saw, such forming the subject matter of my co-pending divisional application, Serial No. 215,287 filed February 4th, 1918, entitled Printing slug sawing device.

I do not herein claim my novel improvements relating to the guiding of the cut portions of the slug as they pass out of the machine, such being described and claimed 55 in my co-pending divisional application, filed February 4th, 1918, Serial No. 215,288, entitled Type-bar casting machines.

The several specific mechanisms herein shown and described are to be understood 60 as being merely a typical embodiment of my invention, for it will be evident that many other forms and constructions will readily suggest themselves to one skilled in the art by means of which to accomplish the results 65 which I attain, and I therefore do not limit

or confine my invention to the specific structures herein shown and described.

I claim:

1. In a linotype machine having a slug mold of a fixed length, an adjustable matrix assembler stop, an adjustable vise jaw for holding the line of matrices in relation to the mold, means for ejecting the slug from the mold, a cutter for cutting the slug as it is ejected and means for simultaneously adjusting said jaw, stop, and cutter to produce a printing slug shorter than the length of the mold. 75

2. A linotype machine provided with means for assembling a line of matrices and a mold adapted to occupy a casting position and an ejecting position, and means for ejecting the slug, an assembler stop for controlling the length of the line of matrices assembled, an adjustable vise jaw related to the casting position of the mold for holding the line of matrices, a cutter related to the ejecting position of the mold for severing the slug cast and means for simultaneously adjusting the assembler stop, the vise jaw, and the slug cutter. 85

3. A linotype machine provided with means for assembling a line of matrices and a mold adapted to occupy a casting position and an ejecting position, means for ejecting the slug, an assembler stop for controlling the length of the line of matrices assembled, an adjustable vise jaw for holding the assembled line of matrices in relation to the casting position of the mold, a saw positioned in front of the ejecting position of the mold for sawing the slug into two pieces as it is ejected, means for simultaneously adjusting the assembler stop, the vise jaw, and the saw to produce a finished slug shorter than the mold. 100

4. A linotype machine provided with means for assembling a line of matrices and a slug mold adapted to occupy a slug-casting position and an ejecting position, means for ejecting the slug, an assembler stop for controlling the length of the line of matrices assembled, an adjustable vise jaw for holding the line of matrices in relation to the casting position of the mold, a cutter related to the ejecting position of the mold for severing a slug as it is ejected, means for simultaneously adjusting the assembler stop, the vise jaw, and the slug cutter, to produce a printing slug shorter than the mold, 115 and means for disconnecting the cutter from said adjusting means for independent movement of the cutter. 120

5. In a linotype machine having a mold for casting slugs, a fixed jaw and a movable jaw associated with the mold for holding a line of matrices, a screw threaded rotatable shaft associated with said movable jaw and carrying a non-rotatable nut for engagement with the jaw to position the movable 125 160

jaw relatively to the fixed jaw, and means for moving the nut and shaft longitudinally without rotating the shaft for locking and unlocking the line of matrices, the jaw being movable in one direction independent of the nut.

6. In a linotype machine having a mold for casting slugs, a fixed jaw and a movable jaw associated with the mold for holding a line of matrices, a screw threaded rotatable shaft associated with said movable jaw and an abutment member adapted to be moved back and forth by the rotation of the shaft to position said movable jaw relatively to the fixed jaw, and means for moving said abutment for locking and unlocking the line of matrices and without rotating the shaft, the jaw being freely movable away from the abutment.

7. In a linotype machine having a mold wheel provided with a slot for casting a slug, said mold being movable from a casting position to an ejecting position, a fixed and a movable vise jaw related to the casting position of said mold for holding a line of matrices shorter than the length of the mold, means associated with the ejecting position of the mold for forcing the slug out of the mold, a saw related to said ejecting position of the mold for cutting the slug as it is ejected, and means for simultaneously adjusting the position of the movable jaw for holding a line of matrices of definite length and for adjusting the position of the saw to cut the slug, as it is ejected, at a point corresponding with the inner end of the movable jaw.

8. In a linotype machine having a mold wheel provided with a slot for casting a slug, said mold being movable from a casting position to an ejecting position, a fixed and a movable vise jaw related to the casting position of said mold for holding a line of matrices, means for forcing the slug out of the mold when in the ejecting position, a saw related to said ejecting position of the mold for cutting the slug as it is ejected, and mechanism operatively connecting the movable jaw and the saw for holding a line of matrices of definite length and for adjusting the position of the saw to cut the slug at a point corresponding with the inner end of the movable jaw.

9. In a linotype machine having means for assembling a line of matrices and a mold 55 wheel provided with a mold adapted to occupy a slug casting position and an ejecting position, an adjustable stop for controlling the length of the line of matrices assembled, a fixed vise jaw and an adjustable vise jaw 60 for holding the assembled line of matrices in relation to the casting position of the mold, an adjustable saw related to the ejecting position of the mold for cutting the slug, and means operatively connecting the three adjustable parts for positioning them to cooperate and produce a slug of the desired length.

10. In a linotype machine having means for assembling a line of matrices and a mold 70 wheel provided with a mold adapted to occupy a slug casting position and an ejecting position, an adjustable stop for controlling the length of the line of matrices assembled, a fixed vise jaw and an adjustable vise jaw 75 for holding the assembled line of matrices in relation to the casting position of the mold, an adjustable saw related to the ejecting position of the mold for cutting the slug as it is ejected, and means connecting said 80 movable vise jaw, assembler stop and saw whereby the adjustment of one of said parts automatically causes the like adjustment of the other two.

11. In a linotype machine having a mold 85 wheel provided with a slot for casting a slug, said mold being movable from a casting position to an ejecting position, a fixed and a movable vise jaw related to the casting position of said mold for holding a line of 90 matrices shorter than the length of the mold, means associated with the mold in its ejecting position for forcing the slug out of the mold, a cutter mounted on the machine for cutting the slug, as it is ejected, at a point 95 related to the relative position of the movable jaw, and means for simultaneously adjusting the positions of the movable jaw and cutter.

In testimony whereof, I have hereunto set my hand, this 10th day of March, 1914, in the presence of two subscribing witnesses.

CHARLES L. MOHR.
